UNITED STATES PATENT OFFICE.

EDWIN W. KIRMES, OF MELROSE, MASSACHUSETTS, ASSIGNOR TO WALWORTH-ENGLISH-FLETT COMPANY, OF BOSTON, MASSACHUSETTS, A CORPORATION OF MASSACHUSETTS.

WATER HEATER.

1,404,973.

Specification of Letters Patent. Patented Jan. 31, 1922.

Application filed April 8, 1920. Serial No. 372,347.

To all whom it may concern:

Be it known that I, EDWIN W. KIRMES, a citizen of the United States, residing at Melrose, county of Middlesex, Commonwealth of Massachusetts, have invented a certain new and useful Improvement in Water Heaters, of which the following is a specification, reference being had therein to the accompanying drawings.

10 My invention has for its object a water heater of a simple and effective character which can be secured to a water faucet and supplied with steam and will mix the water with steam and heat it. It is particularly intended for use in boiler rooms, office buildings, and similar places where there is no supply of hot water but where it is possible to obtain both cold water and steam. The present invention is also particularly adapted for use with low pressure steam systems.

15 The invention will be fully understood from the following description when taken in connection with the accompanying drawings, and the novel features thereof will be pointed out and clearly defined in the claims at the close of this specification.

20 Referring to the drawings, Fig. 1 is a vertical section of a hot water heater embodying my invention.

25 Fig. 2 is a side elevation of the valve cage. Fig. 3 is a section on line 3, 3 of Fig. 2.

Fig. 4 is a section on line 4, 4 of Fig. 1.

30 Referring now to the drawings, at 11 is shown the water chamber provided on its upper side with a screw-threaded connection for attachment to a cold water faucet not shown. The lower part of the water chamber is formed in a separate piece 13 which is secured to the upper part 11 by

35 screw threads 14. This part of the water chamber has a water outlet 17. Within the said water chamber and formed integral with the upper part thereof is a steam chamber 15 the lower portion of which is corrugated to give a greater heat radiating surface as shown in Figure 4. The steam chamber 15 has steam outlet ports 16 communicating with the interior of the water chamber.

40 At 18 is shown a steam inlet passage which is screw-threaded for connection with the steam pipe not shown. Within this steam passage is a valve cage 19 (see particularly Figures 2 and 3). This valve cage is made conveniently of sheet metal and is flanged

as shown at 21 so that it will rest against a shoulder 20 on the steam inlet passage 18. The valve cage 19 is conveniently made from a sheet of metal rolled into cylindrical form and slotted to form ports 23. It is turned in on the ends, as shown at 24 and 25, and contains a ball valve 26 which seats in the right-hand end of the cage and prevents any backward flow from the steam chamber into the steam inlet pipe. This arrangement makes it possible to use the improved hot water heater on low pressure steam systems when it would otherwise be impossible because, as has been found in actual experience with such water heaters, the water will flow through into the steam inlet pipe instead of escaping through the outlet opening 17. The arrangement herein described is simple and effective and entirely prevents any difficulty resulting from low pressure in the steam system.

45 What I claim is,

1. In combination, a water chamber having a water inlet connection, and an outlet port, a steam chamber surrounded by said water chamber and having steam ports communicating with said water chamber, a steam inlet passage extending through said water chamber, and a valve in said inlet passage preventing the flow from the steam chamber back into the steam inlet pipe.

50 2. In combination, a water chamber having a water inlet connection and an outlet port, a steam chamber surrounded by said water chamber and having steam ports communicating with said water chamber, a steam inlet passage extending through the said water chamber, a valve cage insertible through said inlet passage, and a valve in said cage preventing the flow from the steam chamber back into the steam inlet pipe.

55 3. In combination, a water chamber having at the top a water inlet connection for engagement with a water faucet and having an outlet port at the bottom, a steam chamber within said water chamber and having steam ports communicating with said water chamber, a steam inlet passage extending through said water chamber and screw threaded for engagement with a steam pipe, a valve cage having a flange, said cage being insertible through the inlet passage and projecting into the steam chamber and being held in place by the end of the steam pipe.

and a ball valve in said cage preventing the flow from the steam chamber back into the steam inlet pipe.

4. In combination, a steam chamber having a steam inlet passage and outlet ports, a water chamber surrounding said steam chamber and made in two parts, the upper of which is cast integral with the steam chamber and is provided at the top with a

10 water inlet connection for engagement with a water faucet, and the lower of which is

screw-threaded to the upper and is provided with a water outlet port at the bottom, there being a steam inlet passage extending through the upper part of the water chamber 15 into the steam chamber, a valve cage in said steam inlet passage extending into the steam chamber, and a valve therein preventing the flow from the steam chamber back into the steam inlet pipe.

20 In testimony whereof I affix my signature.

EDWIN W. KIRMES.
